GRINDING MACHINE

Hans Ernst, Cincinnati, and Albert H. Dall, Silverton, Ohio, assignors to Cincinnati Grinders Incorporated, Cincinnati, Ohio, a corporation of Ohio

Application October 20, 1936, Serial No. 106,596

22 Claims. (Cl. 51—49)

This invention relates to machine tools and more particularly to improvements in the transmission and control mechanism thereof.

One of the objects of this invention is to provide an improved transmission and control mechanism which is especially adaptable for controlling the relative movements of a grinding wheel in a machine having capacity for relatively large work and in which the movements of the wheel must necessarily be relatively large.

Another object of this invention is to provide a transmission and control mechanism for the purposes described which is comparatively simple in construction, but which is capable of yielding all the desirable control effects necessary to the successful operation of a machine of the above character.

A further object of this invention is to provide a transmission and control mechanism which is capable of yielding a plurality of ranges of feed rates, all in continuous succession, together with infinite variation throughout all ranges.

Other objects and advantages of the present invention should be readily apparent by reference to the following specification, considered in conjunction with the accompanying drawings forming a part thereof and it is to be understood that any modifications may be made in the exact structural details there shown and described, within the scope of the appended claims, without departing from or exceeding the spirit of the invention.

Referring to the drawings in which like reference numerals indicate like or similar parts:

Figure 1 is a plan view of a machine embodying the principles of this invention.

Figure 2 is an end elevation of the machine in the direction indicated by the arrows 2—2 in Figure 1.

Figure 3 is an enlarged cross sectional view through the wheel slide showing the means for adjusting the wheel toward and from the work support.

Figure 4 is a cross sectional view through the wheel head carried carriage taken along the line 4—4 of Figure 1 and showing the final driving means for traversing the carriage.

Figure 5 is a detailed section on the line 5—5 of Figure 4 showing the means for selecting between manual and power traverse of the wheel head and for selecting between the high and low source of feed rates.

Figure 6 is a detailed section on the line 6—6 of Figure 3 showing the means for clamping the cross slide to the traversing slide.

Figure 7 is a fragmentary view with parts broken away looking in the direction of the arrows 7—7 of Figure 6.

Figure 8 is a section on the line 8—8 of Figure 2.

Figure 9 is a detailed section taken on the line 9—9 of Figure 1.

Figure 10 is a detailed sectional view taken on the line 10—10 of Figure 9.

Figure 11 is a detailed view taken on the line 11—11 of Figure 9.

Figure 12 is a sectional view taken on the line 12—12 of Figure 11.

Figure 13 is a diagrammatic view of the transmission and control mechanism of the machine.

Figure 14 is a plan view of the guide plate as viewed on line 14—14 of Figure 5.

Figure 15 is a detail view of the variable delivery pump control.

Figure 16 is a plan view of the control shown in Figure 15.

This invention has been illustrated in connection with a roll grinding machine of the type shown in Figures 1 and 2 which consists of an elongated fixed bed 10 on which is mounted a headstock 11 and a tailstock 12, the latter of which is adjustable toward and from the headstock for set-up purposes. There is also provided a pair of guideways 13 and 14 upon which is slideably mounted a traversing carriage 15 which, in turn, supports a transversely movable wheel head carriage 16.

This invention is concerned with an improved transmission and control mechanism for controlling the transverse movements of the wheel head and the feeding and traversing movements of the carriage 15.

As shown in Figures 3 and 13, the cross slide 16 is actuated by a piston 17 connected by a piston rod 18 to the slide 16 and slideably mounted in a cylinder 19. The opposite ends of this cylinder are connected by channels 20 and 21 to ports 22 and 23 of a manually operable reversing valve 24. This valve has a pressure port 25 connected to the delivery of a constant displacement pump 26 which has an intake 27 through which fluid is withdrawn from a reservoir, indicated generally by the reference numeral 28. The reversing valve 24 has an additional pair of ports 29 and 30 connected to a return line 31.

The plunger 32 of the reversing valve is connected by a crank 33 to an operating handle 34. When the plunger 32 is shifted to the right, as indicated in Figure 13, the pressure port 25 is connected to port 23 whereby fluid is delivered to one end of cylinder 19 to cause the wheel head

16 to move toward the work support and when the plunger 32 is shifted to the left of the position shown in Figure 13 the port 25 is then connected to port 22 to cause return movement of 5 the wheel head. Thus, through the medium of the manual control the wheel head slide may be moved by power. This mechanism is for the purpose of making rough adjustments of the grinding wheel for set-up purposes, and since, as 10 a matter of fact, each roll that is ground is usually of a different size it becomes necessary to adjust the grinding wheel for practically every piece of work.

To insure, however, that the grinding wheel 15 maintains a definite position with respect to the slide 15 and that there is no creepage due to the slight variations in pressure in the opposite end of cylinder 19, a clamping mechanism has been provided for securing the slide 16 to the slide 15. 20 The details of this clamping mechanism, which are more particularly shown in Figures 6, 7 and 8, comprise a pair of pull rods 35 and 36 located on opposite sides of the V guide-way 37 and the upper ends of these rods pass through L-shaped 25 clamping members 38 and 39 respectively and are threaded to receive lock nuts 40. The lower ends of these rods are connected to an equalizer bar 41 which is adapted to be engaged in the middle by a pivoted clamping lever 42. 30 This lever, as shown in Figure 7, is pivotally mounted at one end on a fixed stud 43 and at the other end rotatably supports a cam 44 which is actuated by the ball-ended crank 45. The cam 44, which is circular, is eccentrically supported on 35 the shaft 46 and when the parts are in the clamping position shown in Figure 7, the largest radius of the cam engages the undersurface of the block 47, thereby holding the lever 42 downward which thereby applies pressure on the equalizer bar 41 and rods 35 and 36 to cause the clamping members 38 and 39 to hold the slide in a fixed position. 40 The cam is moved into this position by the application of fluid pressure on the end of the piston 48 and the clamps are released by applying fluid pressure on the end of the piston 49. 45 As shown, these pistons bear on the ball-shaped crank 45, piston 48 tending to rotate the parts in a counter-clockwise direction and the piston 49 tending to rotate the parts in a clockwise direction. 50 The pistons 48 and 49 are contained in cylinders 50 and 51 respectively and these cylinders are connected by channels 52 and 53 respectively to ports 54 and 55 of a reversing valve 56 having a central pressure port 57 and return 55 ports 58 and 59 on opposite sides thereof. The plunger 60 of this reversing valve is urged by a spring 61 in such a direction that the pressure port 57 is connected to the port 54 leading to cylinder 50 whereby the cross slide 16 is clamped 60 to the traversing slide 15. Pressure is supplied to the port 57 from a branch line 62 which is supplied with fluid from the constant displacement pump 26.

It is, of course, obvious that the clamping 65 mechanism should be released before the slide is moved and to this end means have been provided whereby the lever 34 will actuate the reversing valve of the clamping control mechanism, before it finally shifts the plunger 32 into a position to effect pressure connections to the cross slide actuating cylinder 19. This mechanism comprises a lever 63 having one end pivoted at 64 and the other end engaging the plunger 60. An intermediate V-shaped portion 65 of the lever is 70 adapted to engage a notch 66 in the periphery of

a plate 67 fixed for movement with the lever 34. The notch permits the spring 61 to shift the plunger 60 into the position shown in Figure 13, whereby pressure is connected to cylinder 50. Upon movement of the lever 34 in either direction from the central position in which it is shown, the lever 63 will be moved in a clockwise direction about its pivot 64 and shift the plunger 60 to the right and thereby cause fluid pressure to be connected to cylinder 51 with a resultant release of the clamping mechanism. As the lever 34 moves to shift the plunger 60 it is also moving the reversing valve plunger 32, but this plunger has sufficient overlap with respect to its ports that appreciable movement may be effected before pressure is connected into lines 20 and 21. Since a certain time element is involved in effecting unclamping and to prevent dissipation of the pressure, which would happen if the operator moved the lever 34 quickly to 25 either of its extreme positions, an interlock has been provided which limits the movement of the valve plunger 32 so that it will not attain an operative position until the clamping mechanism has been released.

This mechanism includes a notched plate 68 integrally connected for movement by the handle 34, and a spring-pressed pawl 69 adapted to be held in engagement with said notch, the notch being of sufficient width to allow a certain amount of lost motion between the pawl and the plate whereby the lever 34 may be moved a sufficient amount to cause shifting of the reversing valve 60 to a clamp unlocking position while still preventing movement of the plunger 32 to a slide actuating position. The pawl 69 is pivoted at an intermediate point 70, and a fluid actuated plunger 71 engages the other end of the pawl for withdrawing the same from engagement with the plate 68. The plunger 71 is slideably mounted in a cylinder 72 which is connected by a channel 73 to a port 74 located in the cylinder 51. When the plunger 49 has moved a sufficient distance to release the clamp, the channel 53 which supplies fluid pressure to cylinder 51, is interconnected with port 74 whereby the fluid pressure will be connected to cylinder 72 to cause withdrawal of the pawl and permit further movement of the lever 34. Upon return movement of the lever 34 to its central position, the plunger 48 will be actuated to move the crank 45 into a clamping position, a cannelure 75 formed in the plunger 49 will interconnect port 74 with exhaust port 76, whereby a spring 69' may return lever 69 into an interlocking position and effect retraction of piston 71.

Thus, the first part of the movement of the lever 34 from its central position shifts the reversing valve 60 into a position to cause unclamping of the slide by connecting pressure to line 53; and completion of the unclamping operation automatically releases the lever 34 for further movement in the same direction by connecting pressure to cylinder 72, whereby the reversing valve 32 may be shifted into a position to cause movement of the slide. Upon return movement of the lever, the various steps take place in reverse order, the movement of the slide being stopped first by the reversing valve 32, followed by clamping of the slide and resetting of the locking pawl.

In roll grinders it is desirable to have a transmission which is infinitely variable over a comparatively wide range, and with this requirement in view, a transmission and control mechanism

has been provided which will yield a minimum rate of approximately 1" travel of the slide per minute and a fast rate of approximately 120" per minute, together with the feature of variation 5 between these limits.

It is also desirable that this transmission be of a type which readily lends itself to manual operation.

A careful selection of the elements making up 10 this transmission has been made, in view of the fact that a piston and cylinder type of motor does not readily lend itself to manual operation of the slide, and because an electric motor of the variable speed type is limited to a range of 1 to 3 15 so far as infinite variation of speed is concerned. The units of the transmission, therefore, consist of a variable delivery pump and a variable speed fluid motor, which makes it possible to obtain an infinite range from 1 to 20, which makes possible infinite variations of travel from 1" to 20" per 20 minute of the slide. Additional variation is obtained by combining a constant delivery pump having an output equal to the maximum output of the variable delivery pump whereby the range 25 may be increased to obtain infinite variation of rate from 20" to 40" of travel a minute. In either of the above cases, the variable speed hydraulic motor is connected by reduction gearing to the final output, and by reducing this reduction 30 by the factor 4, the first range is increased to yield infinite variation of rate over a third range from 40" to 80", and the second range increased to yield an infinite variation of rate over a fourth range from 80" to 120" per minute, 35 and all in continuous succession.

The transmission and control mechanism for traversing the wheel head relative to the work support will now be described. The fixed bed 78 on which the guide ways 13 and 14 are mounted 40 for supporting the carriage 15 is provided with a rack 79 which is engaged by a pinion 80, as shown in Figure 4, secured to the end of a vertical shaft 81. The shaft 81 is journaled in the carriage 15 on anti-friction bearings and is rotated by a 45 worm wheel 82 which is, in turn, driven by a worm 83. Referring to Figure 5, the worm 83 is supported on a shaft 84 which has mounted for free rotation thereon a pair of spur gears 85 and 86, gear 85 being larger in diameter than gear 86. These gears are in constant mesh with gears 50 87 and 88 respectively keyed to shaft 89. This shaft is directly connected for rotation by an hydraulic motor 90. The gear train 87-85 effects in this case a rate reduction of four times that effected by train 88-86, but it is to be 55 understood that other reductions could be utilized.

The clutch 91 is splined on shaft 84 intermediate gears 85 and 86 and has clutch teeth 60 formed on opposite faces for engagement with similarly formed clutch teeth on the opposing faces of the gears. Since the gear 85 is continuously driven at a slower rate than the gear 86, and since the motor 90 can be driven at a plurality of rates it will be apparent that the clutch member 90 serves to select between a high series and a low series of feed rates.

The clutch 91 is shifted by a shifter fork 92 fixed on the shifter rod 93. The shaft 84 has a 65 gear 94 fixed to the end thereof and adapted to be interengaged by a shiftable gear 95 for manual rotation of the worm 83. The gear 95 is splined on a shaft 96 to the end of which is secured a large sprocket wheel 97 and connected by a chain 70 75 98 to a sprocket pinion 99. This pinion is keyed

to a shaft 100 which is carried in a bracket 101 which rises from the support so as to position the hand wheel 102 which is secured to the end of shaft 100 in a convenient position for actuation by the operator. It will now be apparent 5 that when the gear 95 is intermeshed with the gear 94 that the hand wheel 102 may be rotated to effect translation of the carriage 15.

The gear 95 is shifted by a fork 103 which is secured to a shifter rod 104. In order to prevent 10 conflict between manual and power operation of the worm 83, the shifter rods 93 and 104 are arranged side by side and a common control lever 105 is provided, and provision made whereby this lever can only shift the clutch 91 or the 15 gear 95 into an operative position at a time. In other words, the lever 105 is pivotally mounted at an intermediate point by means of a ball-shaped portion 106 and a guide plate 107 is provided in which is formed a slot 108 having a 20 shape such as that shown in Figure 14. The lever 105 is moved laterally through the portion 109 of the slot to select which shifter rod is to be moved and is movable through the portion 110 to shift the clutch 91 into either one of its two 25 positions and through the portion 111 to shift the gear 95 into engagement with gear 94.

Operating fluid is supplied to the motor 90 by a variable displacement pump 112 having intake and delivery ports 113 and 114 respectively which 30 are operatively connectible by channels 115 and 116 to ports 117 and 118 of a stop valve 119. The plunger 120 of this valve is shown in a stop position in Figure 13, but when the same is shifted to the right of that position the cannelure 35 121 interconnects port 118 with port 122, and thereby through channel 123 to port 124 of a reversing valve 125. In addition the cannelure 126 interconnects port 117 with port 127, thereby through channel 128 to ports 129 and 130 of reversing valve 125. The reversing valve also has a pair of ports 131 and 132 to which are connected channels 133 and 134 respectively through which fluid is supplied to the motor 90. When the reversing valve plunger 135 is in its right hand position, as shown, the pressure is delivered into channel 133 from the delivery port 114 of the pump 112 and the fluid returning through channel 134 is returned by way of port 130, channel 128, ports 127 and 117 of the stop valve and channel 115 to the intake port 113 of the variable delivery pump. It will be seen that this is in effect a closed circuit with the intake and delivery ports of the pump connected directly to the two ports of the motor. 55

The reversing valve plunger 135 is power shifted by fluid operable pilot circuit comprising a pilot valve 136 having a pressure port 137 connected by channel 138 to the delivery channel 116 of the variable delivery pump 112. Also, the pilot valve has a pair of return ports 139 and 140 which are connected to channel 141 leading to the intake line 115 of the variable delivery pump. In addition, the pilot valve has a second pair of ports 142 and 143 which are connected by channels 144 and 145 respectively to opposite ends of the reversing valve 125. When the plunger 146 of the pilot valve is in its right hand position, as shown in Figure 13, pressure from port 137 will flow to the left end of valve 125 shifting 70 plunger 135 into its right hand position and when the pilot valve plunger 146 is shifted to the left, pressure from port 137 will then be delivered to the right hand end of valve 125, shifting plunger 135 to its left hand position. 75

The pilot valve plunger 146 is connected by a bell crank 147, shown in Figure 12, to a vertical movable slide 148 in which is formed a slot for receiving one arm 149 of the bell crank. The slide 148 is provided with a T slot 150 to which may be secured a pair of adjustable dogs 151. The slide is guided by an elongated gib 152 on one side and a pair of short gib 153 located on the other side.

Due to the extremely long traversing movement of the wheel head, mechanism has been provided for proportionately shortening this movement so that it is unnecessary to provide a long dog carrying slot, and furthermore to make it possible to provide a tripping mechanism which may be self-contained in the slide. To this end a screw 154 is rotatably supported adjacent to and parallel to the dog carrying slide 148, and has threaded thereon a trip member 155 which has a projecting portion on one side adapted to engage the dogs 151 and a guiding portion 156 on the other side which is engaged by a gib 157 to prevent rotation of the nut member. One end of the screw is operatively connected to a sprocket wheel 158 which is connected by a chain 159 to a sprocket pinion 160 secured to the upper end of shaft 81, as more particularly shown in Figure 4. It should now be apparent that as the shaft 81 rotates, it rotates the screw 154, causing the nut member 155 to travel along the screw. The front of the housing 161 in which this tripping mechanism is contained is provided with a door 162 on one side and supported on hinges 163 whereby the operator may have ready access to the dog carrying slide, but still permitting the entire mechanism to be enclosed and protected.

The pilot valve plunger 146 may also be shifted manually at will by means of the control lever 164 which is keyed to the shaft 165 to which, in turn, is connected the bell crank 147. Thus, the pilot valve may be shifted manually at will, or automatically actuated from the moving carriage. The stop valve plunger 120 is operated by the manual control lever 166 which is fixed to shaft 167 journaled in the upper part of the casing 161 and provided on the lower end with a crank arm 168 engaging a cross slot formed in the end of plunger 120.

Means have been provided for obtaining a tarry at each reversal of the wheel carriage and this mechanism is interposed between the direction control valve 125 and the hydraulic motor 90. The mechanism comprises a double resistance throttle valve 169 in which is contained a plunger 170. This plunger has a pair of annular grooves 171 and 172 formed therein and adapted to lie opposite ports 173 and 174 respectively, which ports are connected by channels 175 and 176 to opposite ends of a shuttle valve 177. The grooves 171 and 172 are provided with tapered portions 178 and 179 which lie opposite ports 180 and 181 and serve to form variable hydraulic resistances. The ports 180 and 181 are connected to channels 133 and 134 which come from the reversing valve 125. Since the channels 133 and 134 are alternately connected to pressure and exhaust it will be apparent that in the position of the parts shown and with pressure in line 133 that fluid will flow through port 180 and hydraulic resistance 178, groove 171, port 173, and channel 175 to the left end of valve 177, while the opposite end is connected to exhaust. This means that the plunger 182 should be shifted to the right in the position as shown. When the re-

versing valve shifts, however, the pressure in line 134 must pass through the resistance 179 and eventually build up a pressure in the right hand end of valve housing 177 and the fluid in the other end must be forced outward through resistance 178. The amount of time that this will take will depend, of course, upon the value of the resistances 178 and 179 and these may be varied to obtain various lengths of tarry.

The mechanism for effecting this adjustment 10 consists of a spring 183 which acts on one end of plunger 182 to shift it in a direction to reduce the valve of the hydraulic resistances and an adjustable pin 184 for limiting the movement. As shown in Figure 10, the pin 184 abuts the 15 end of a crank 185 secured to a rotatable shaft 186. This shaft carries a forked lever 187 in the end of which is pivotally connected a nut 188 threaded on an adjusting screw 189. This adjusting screw has an operating handle 190 on one 20 end whereby the screw may be rotated to variably position the stop pin 184. In order to insure that pressure built up in either channel 133 or 134 when the same is connected to pressure and to prevent operation of the hydraulic motor 90 25 until the proper amount of time has elapsed, the plunger 182 is provided with a pair of self-contained check valves, indicated generally by the reference numerals 191 and 192. The plunger 182 is provided with annular grooves 193 and 194 30 whereby when the plunger 182 is shifted to the right the groove 193 will interconnect port 195 with motor line 196 and when shifted to the left the groove 194 will interconnect port 197 with motor line 198. In other words, the pressure 35 fluid delivered by pump 114 will pass through either groove 193 or groove 194. It will be noted that the ports 195 and 197 are connected to the channels 133 and 134 which lead from the reversing valve.

In addition, the plunger 182 is provided with a second pair of grooves 199 and 200 which are always exhaust grooves. In other words, when the plunger 182 is in its right hand position the groove 200 receives the exhaust flow from the 45 motor 90 through channel 198, and when the plunger is in its left hand position the groove 199 receives the exhaust flow from motor channel 196. The grooves 199 and 200 have cross bores 201 and 202 respectively formed therein 50 which intersect longitudinal bores 203 and 204 respectively. The bore 203 is enlarged to receive a spring pressed ball check 205 which is adapted to be opened when the groove 199 is in communication with motor channel 196, but which 55 is otherwise closed. The groove 193 also has a cross bore 206 which intersects the longitudinal bore whereby the return fluid may escape through port 195, but when port 195 is a pressure port the incoming fluid cannot be forced past the 60 check valve. The same construction is provided in the other end of the valve plunger whereby the exhaust fluid may be passed from channel 198 to port 197 but when port 197 is a pressure port the fluid cannot escape past the check valve. 65 It will now be seen that with the parts in the position shown if the reversing valve be shifted to make port 197 a pressure port, fluid would not be able to pass the check valve into annular groove 200 which means that the pressure would 70 rise and pass through the resistance 179 into the right hand end of valve 177 and continue to rise until the valve plunger 182 is shifted into its left hand position, at which time the groove 194 would then directly connect port 197 to motor line 198. 75

If no tarry is desired it will be apparent that the plunger 170 may be adjusted to its extreme left hand position whereby the shuttle valve plunger will immediately shift upon reversal in 5 the direction of flow and without delay.

As previously mentioned, the variable delivery pump 112 has a certain range, and in order to increase this range and maintain the infinite variation feature, use is made of the constant delivery pump 26, which has a displacement equal to the maximum displacement of the variable delivery pump, and the output of the constant displacement pump is combined with the other pump by means of valve 207. In order to 10 make the supply from pump 26 available for this purpose, when it is not being utilized for clamping purposes, an interlock 208, Figure 13, is provided, and this valve serves to connect channel 52 to channel 211. It will be noted that when 15 the plunger 213 of the interlock valve is in its left hand position, as shown, that the line 52 which is under pressure at this time is connected to port 210, whereby the port 212 of valve 207 becomes a pressure port and will remain a pressure port at all times when the cross slide is 20 clamped.

The valve 208 is really connected across the lines 52 and 53; and has one end port connected by branch 209 to channel 52, and the other end port connected by a check valve 214 to line 53, whereby, when channel 52 is under pressure the plunger 213 will be shifted to the left, as viewed in Figure 13; and when channel 53 is under pressure the plunger 213 will be shifted to the right. 25 During normal operation of the machine, the plunger 213 is in the position shown in Figure 13, with pressure existing in line 52. When the reversing valve 56 is moved to a position to effect unclamping of the cross slide, it is necessary that 30 the plunger 213 be immediately shifted to the right, which the check valve 214 permits, so that when pressure is reconnected to channel 52 the circuit will be in a condition to cause sufficient pressure to build up in channel 52 to operate 35 the clamping mechanism. It is, therefore, necessary to prevent dissipation of pressure through the channel 211, which might be connected to the reservoir at any time, and to this end, means have been provided for preventing immediate 40 shifting of plunger 213 into its left hand position, consisting of the choke coil 215 and the valve associated with plunger 71. In other words, the plunger 71 has a cannelure 217 which, when the plunger 71 has been retracted by the spring 69' 45 acting on the lever 69, serves to interconnect port 216, to which the outlet of the choke coil 215 is connected, with the exhaust port 218. The choke coil and valve act as a delay means to prevent shifting of the plunger 213 until the slide 50 has been securely clamped. When the plunger 213 has completed its shifting movement to the left it interconnects branch line 209 to port 210 and channel 211, thereby rendering the output of the constant displacement pump available for 55 use in the supply circuit for motor 90.

It will be noted that when valve plunger 219 is to the right, as shown in Figure 13, the port 212 is connected by cannelure 220 to port 221 leading to the exhaust line 222. This permits the 60 constant delivery pump 26 to be by-passed to reservoir, but since the fluid must pass through the relief valve 223 it will be apparent that the system will be maintained full of oil at a low pressure.

5 The plunger 219 is shifted by a crank arm 224

as shown in Figure 12, which is attached to the end of a vertical shaft 225 terminating in a manual control lever 226. When this lever is actuated to shift the plunger 219 to its extreme left position, as viewed in Figure 13, a cannelure 5 227 formed in the plunger interconnects port 212 with port 228 whereby the delivery from the constant displacement pump 26 is added by way of channel 229 to the flow from the variable delivery pump 114 passing through channel 123. At 10 the same time, a cannelure 230 interconnects a branch 231 of return line 128 to the return line 222. This is necessary because it must be remembered that the variable displacement pump is connected in practically a closed circuit to the 15 hydraulic motor 90 and when the fluid from the constant displacement pump is added to one side of this closed circuit, there will be an extra quantity being returned to the pump 114 which cannot be accommodated. Therefore, this connection permits the excess fluid to be by-passed to reservoir through the check valve 223 and thereby replenish the supply to the constant delivery pump.

In Figures 15 and 16, there is shown the means 25 for controlling the displacement of the variable delivery pump 112, and this means comprises a cam 232 attached to the lower end of shaft 233 against which is adapted to bear the pintle 234 of the variable delivery pump. A handle 235 is 30 secured to the upper end of shaft 233 whereby the cam may be rotated to vary the displacement of the pump.

As shown in Figure 16, a chart 236 is associated 35 with the handle 235 upon which may be placed suitable indicia whereby the operator may determine the feed rate for any given setting of the controls. There may be four concentric arcs, with the indicia on the first arc indicating the rates available when the constant displacement 40 pump 26 is disconnected from the circuit, and the clutch 91, shown in Figure 5, is in its left hand position; the indicia on the second arc indicating the rates available when the output of the constant displacement pump has been coupled 45 with the output of the variable displacement pump; the indicia on the third arc indicating the rates available when the constant displacement pump has been disconnected from the circuit and the clutch 91 is shifted into its right hand position as shown in Figure 5; and the indicia on the fourth arc indicating the rates available when both pumps have been combined to supply the motor 90, and the clutch 91 is in its right hand position. It will thus be apparent that there are 50 four ranges of speed and each range is a continuation of the preceding one and without steps.

There has thus been provided an improved transmission and control circuit which is especially adaptable for machines of the roll grinding 60 type having long traversing movements and in which is incorporated in simplified form mechanism for obtaining all the desirable control functions.

What is claimed is:

1. In a machine tool having relatively movable work and tool supports, the combination of transmission means for effecting said relative movement including an hydraulic motor operatively connected to one of said supports, a conduit system for supplying actuating medium to the motor including a reversing valve, a variable delivery having intake and delivery ports connected to said reversing valve, and means including a shiftable valve interposed in the sys- 75

tem between said reversing valve and said motor, and responsive to shifting of said reversing valve, to decelerate, stop, and accelerate in an opposite direction the moving slide.

- 5 2. In a machine tool having relatively movable work and tool supports, the combination of transmission means for effecting said relative movement including an hydraulic motor operatively connected to one of said supports, a reversing valve, a variable delivery pump having intake and delivery ports connected to said reversing valve, means interposed between said reversing valve and said motor and responsive to shifting thereof to decelerate, stop, and accelerate in an opposite direction the moving slide, said means including a delay valve and a valve having self-contained check valves effective to build up a shifting pressure when the flow is reversed to said motor to cause a slow movement of the last-mentioned valve and thereby a tarry of said motor.

- 25 3. In a machine tool having relatively movable work and tool supports, the combination of transmission means for effecting said movement including an hydraulic motor, a reversing valve, a variable delivery pump having intake and delivery ports connected to said valve, means in said valve for connecting said delivery port for reversible operation of said motor, a constant delivery pump, selectively operable means for connecting delivery of said constant displacement pump for combination with the delivery of said variable displacement pump for increasing the movement of said motor to a rapid traverse rate, 35 a stop valve interposed in the delivery channel of said variable delivery pump and effective to connect the same to the intake of said variable delivery pump, and means for simultaneously connecting the constant delivery pump output to 40 reservoir.

- 45 4. In a grinding machine having relatively movable tool and work supports and an hydraulic motor for effecting said movement, the combination of a tarry mechanism including a shiftable plunger having a pair of self-contained check valves, a pair of ports connected to said motor, a second pair of ports alternatively connectible to intake and delivery ports of a variable delivery pump, said check valves being effective to pass 50 return fluid from said motor and block delivery of fluid to said motor, and means responsive to the pressure of said blocked fluid to shift said plunger into a position by-passing said check valve when subject to pressure.

- 55 5. In a machine tool having a work support and a tool support, the combination with hydraulic means for effecting relative translation between the supports including an hydraulic motor and a reversing valve therefor, of a tarry valve interposed between the reversing valve and the motor, said tarry valve including a shiftable plunger, a pair of ports connected to said reversing valve and adapted to be alternately subjected to pressure thereby, branch connections from each of 60 said ports to the respective ends of said valve, said connections having variable resistances therein, means in the valve responsive to reversal of flow therethrough to block the pressure flow to said motor, and simultaneously cause a slow 65 increase in pressure on one end of said valve to effect shifting of the same, and means effective upon completion of said shifting movement to connect the pressure flow to said motor.

- 70 6. In a grinding machine having a work support and a grinding wheel support, the combi-

nation of transmission mechanism for traversing one of said supports relative to the other at infinitely variable rates including a rotary hydraulic motor, a variable displacement pump, a constant displacement pump having an output equal to 5 the maximum output of said variable displacement pump, a rate changer connecting said motor to said traveling support, a first valve means for connecting the first-named pump to said motor to produce a first range of speeds, a second 10 valve means for connecting the second-named pump to said motor simultaneously with the first-named pump to produce a second range of speeds, and means to adjust said rate changer to produce a plurality of other ranges of speeds. 15

7. In a grinding machine having a work support and a grinding wheel support, the combination of a transmission for effecting relative movement between the supports including a final drive shaft operatively connected to the moving 20 support, a rotary hydraulic motor, different ratio gear trains continuously driven by said motor, a plurality of pumps selectively connectible in different combinations to said motor to yield a plurality of rates of actuation thereof, a manual 25 actuator for said final shaft, means to couple selectively said manual actuator to said shaft, means to couple selectively either of said gear trains to said shaft, said last-named means also being operable to disconnect simultaneously both 30 of said gear trains from said shaft, and a common control for all of said coupling means.

8. In a grinding machine having a work support and a grinding wheel support, the combination of a transmission for effecting relative movement between the supports including a final drive shaft operatively connected to the moving support, a rotary hydraulic motor, different ratio gear trains continuously driven by said motor, a plurality of pumps selectively connectible in 40 different combinations to said motor to yield a plurality of rates of actuation thereof, a manual actuator for said final shaft, means to couple selectively said manual actuator to said shaft, means to couple selectively either of said gear 45 trains to said shaft, said last-named means also being operable to disconnect simultaneously both of said gear trains from said shaft, a common control lever for all of said coupling means, and an interlocking guide plate for said lever whereby when said manual actuator is connected to the final shaft, said motor will be disconnected therefrom and vice versa.

9. In a grinding machine having relatively movable tool and work supports and a fluid operable motor for effecting said movement in opposite directions, the combination with a pump for supplying fluid to said motor and a reversing valve, of a tarry mechanism including a shiftable plunger having a pair of self-contained check 55 valves, a pair of motor channels, a second pair of channels adapted to be reversibly connected by said valve to the output of said pump, means interconnecting said plunger with all of said channels whereby said check valves are effective to 60 pass return fluid from said motor and block delivery of fluid to said motor upon shifting of said reversing valve, and means movable in response to the pressure of said blocked fluid to shift said plunger into a position rendering said check 65 valves ineffective.

10. I. A machine tool having a work support and a grinding wheel support, the combination of an hydraulic circuit for effecting relative movement between the supports including a fluid oper- 75

able motor operatively connected to the moving support, a variable delivery pump having intake and delivery channels connected thereto, a stop valve for interconnecting said channels to stop said motor, a reversing valve having pressure and return ports adapted to be separately connected to said pump channels by said stop valve, variable automatic tarry mechanism interposed in the circuit connecting said reversing valve to said motor, and a pilot valve and control circuit for controlling the shifting of said reversing valve.

11. A machine tool having relatively movable work and tool supports, the combination of transmission means for effecting said movement including a hydraulic motor, an actuating pump therefor and means for controlling the actuation of the motor by the pump including a pilot valve, a reversing valve operable by the pilot valve, an auxiliary reversing valve coupled with the first-mentioned reversing valve and actuatable thereby for determining the ultimate coupling of the actuating fluid from the pump to the motor, and an adjustable tarry mechanism coupled with said second reversing valve for controlling the rate of movement thereof.

12. A machine tool having relatively movable work and tool supports, the combination of transmission means for effecting said movement including a hydraulic motor, an actuating pump therefor and means for controlling the actuation of the motor by the pump including a pilot valve, a reversing valve operable by the pilot valve, an auxiliary reversing valve coupled with the first-mentioned reversing valve and actuatable thereby for determining the ultimate coupling of the actuating fluid from the pump to the motor, an adjustable tarry mechanism coupled with said second reversing valve for controlling the rate of movement thereof, and additional means for diverting the flow from said pump as respects said motor and valve mechanisms.

13. In a machine tool embodying a support and a plurality of members movable thereon with respect thereto, transmission means for effecting movement of the supports including hydraulic motors individual to the respective supports, a closed circuit including a first fluid pump individual to one of said motors for controlled actuation thereof, a second hydraulic pump, and means for selectively coupling said pump with either of said motors, said means including discharge conduits individual to the respective pumps, and valve means for coupling the respective conduits and simultaneously establishing a reservoir connection for said first motor whereby the two pumps may be additively employed for actuation of one of said motors.

14. In a machine tool embodying a support and a plurality of members movable thereon with respect thereto, transmission means for effecting movement of the supports including hydraulic motors individual to the respective supports, a closed circuit including a first fluid pump individual to one of said motors for controlled actuation thereof, a second hydraulic pump, and means for selectively coupling said pump with either of said motors, said means including discharge conduits individual to the respective pumps, and valve means for coupling the respective conduits and simultaneously establishing a reservoir connection for said first motor whereby the two pumps may be additively employed for actuation of one of said motors, and selector means for rendering either or both of said pumps ineffective for actuation of said motors.

15. In a machine tool having relatively movable work and tool supports, means for clamping one of said supports and hydraulic actuators for effecting movements and clamping of the supports, means for effecting controlled hydraulic actuation of said parts including a hydraulic pump selectively coupled with said support motors and operatively associated with the clamp mechanism, a plurality of reversers individual to the motor and clamp mechanisms, a first interlock mechanism between the clamp control reverser and one of the motor reversers for determining the sequential operation of said parts, conduit means extending from the pump output to the second motor reverser, and a hydraulic interlock operatively associated with one of the first-named reversers for determining the flow through the conduit to said last-named reverser.

16. In a machine tool having relatively movable work and tool supports, means for clamping one of said supports and hydraulic actuators for effecting movement and clamping of the supports, means for effecting controlled hydraulic actuation of said parts including a hydraulic pump selectively coupled with said support motors and operatively associated with the clamp mechanism, a plurality of reversers individual to the motor and clamp mechanisms, a first interlock mechanism between the clamp control reverser and one of the motor reversers for determining the sequential operation of said parts, conduit means extending from the pump output to the second motor reverser, a hydraulic interlock operatively associated with one of the first-named reversers for determining the flow through the conduit to said last-named reverser, a first tarry mechanism for determining the flow condition in said interlock controlled conduit, and a second tarry mechanism for determining the time lag in directional reaction of the fluid transmitted by the conduit on the second support shifting motor in response to given adjustments of its reverser.

17. A machine tool having relatively movable work and tool supports including means for shifting one of said supports and means for clamping said support against shifting movement, a first hydraulic motor for effecting shifting of the support, an additional hydraulic motor mechanism for controlling the clamp, and a hydraulic control and actuation system for said parts including a source of hydraulic fluid, a first reverser for coupling the hydraulic medium to actuate the support in reverse directions, a second reverser coupling the hydraulic fluid for movement of the clamp into engaging or releasing position, a single actuator controlling the movement of both reversers, an interlock between said reversers whereby coupling of hydraulic medium for actuation of the support is prevented when the clamp is engaged, and a delay mechanism for determining the sequential operation of the reversers by their common actuator.

18. A machine tool having relatively movable work and tool supports including means for shifting one of said supports and means for clamping said support against shifting movement, a first hydraulic motor for effecting shifting of the support, an additional hydraulic motor mechanism for controlling the clamp, and a hydraulic control and actuation system for said parts including a source of hydraulic fluid, a first reverser for coupling the hydraulic medium to actuate the support in reverse directions, a second reverser coupling the hydraulic fluid for movement of the clamp into engaging or releasing

- position, a single actuator controlling the movement of both reversers, an interlock between said reversers whereby coupling of hydraulic medium for actuation of the support is prevented when the clamp is engaged, a delay mechanism for determining the sequential operation of the reversers by their common actuator, a second shiftable support, a hydraulic motor for actuation thereof, and means for conditioning the hydraulic circuit by way of one of said reversers whereby the hydraulic actuating medium is rendered available for actuation of said second support shifting motor.
19. A machine tool having relatively movable work and tool supports including means for shifting one of said supports and means for clamping said support against shifting movement, a first hydraulic motor for effecting shifting of the support, an additional hydraulic motor mechanism for controlling the clamp, and a hydraulic control and actuation system for said parts including a source of hydraulic fluid, a first reverser for coupling the hydraulic medium to actuate the support in reverse directions, a second reverser coupling the hydraulic fluid for movement of the clamp into engaging or releasing position, a single actuator controlling the movement of both reversers, an interlock between said reversers whereby coupling of hydraulic medium for actuation of the support is prevented when the clamp is engaged, a delay mechanism for determining the sequential operation of the reversers by their common actuator, a second shiftable support, a hydraulic motor for actuation thereof, means for conditioning the hydraulic circuit by way of one of said reversers whereby the hydraulic actuating medium is rendered available for actuation of said second support shifting motor, and an additional serially arranged reversing mechanism in said circuit for determining the direction of actuation of said second support motor.
20. A machine tool having relatively movable work and tool supports including means for shifting one of said supports and means for clamping said support against shifting movement, a first hydraulic motor for effecting shifting of the support, an additional hydraulic motor mechanism for controlling the clamp, and a hydraulic control and actuation system for said parts including a source of hydraulic fluid, a first reverser for coupling the hydraulic medium to actuate the support in reverse directions, a second reverser coupling the hydraulic fluid for movement of the clamp into engaging or releasing position, a single actuator controlling the movement of both reversers, an interlock between said reversers whereby coupling of hydraulic medium for actuation of the support is prevented when the clamp is engaged, a delay mechanism for determining the sequential operation of the reversers by their common actuator, a second shiftable support, a hydraulic motor for actuation thereof, means for conditioning the hydraulic circuit by way of one of said reversers whereby the hydraulic actuating medium is rendered available for actuation of said second support shifting motor, and additional means for rendering said available hydraulic medium ineffective as respects said second support shifting motor.
21. A machine tool having relatively movable work and tool supports including means for shifting one of said supports and means for clamping
- said support against shifting movement, a first hydraulic motor for effecting shifting of the support, an additional hydraulic motor mechanism for controlling the clamp, and a hydraulic control and actuation system for said parts including a source of hydraulic fluid, a first reverser for coupling the hydraulic medium to actuate the support in reverse directions, a second reverser coupling the hydraulic fluid for movement of the clamp into engaging or releasing position, a single actuator controlling the movement of both reversers, an interlock between said reversers whereby coupling of hydraulic medium for actuation of the support is prevented when the clamp is engaged, a delay mechanism for determining the sequential operation of the reversers by their common actuator, a second shiftable support, a hydraulic motor for actuation thereof, means for conditioning the hydraulic circuit by way of one of said reversers whereby the hydraulic actuating medium is rendered available for actuation of said second support shifting motor, an additional serially arranged reversing mechanism in said circuit for determining the direction of actuation of said second support motor, said mechanism including a primary and a secondary reversing valve, and additional delayed action combined decelerating and reversing valve actuatable by the secondary reverser, and delay means for determining the responsiveness of the last-mentioned valve to the reverser in coupling the controlled hydraulic actuating medium to said second support shifting motor.
22. A machine tool having relatively movable work and tool supports including means for shifting one of said supports and means for clamping said support against shifting movement, a first hydraulic motor for effecting shifting of the support, an additional hydraulic motor mechanism for controlling the clamp, and a hydraulic control and actuation system for said parts including a source of hydraulic fluid, a first reverser for coupling the hydraulic medium to actuate the support in reverse directions, a second reverser coupling the hydraulic fluid for movement of the clamp into engaging or releasing position, a single actuator controlling the movement of both reversers, an interlock between said reversers whereby coupling of hydraulic medium for actuation of the support is prevented when the clamp is engaged, a delay mechanism for determining the sequential operation of the reversers by their common actuator, a second shiftable support, a hydraulic motor for actuation thereof, means for conditioning the hydraulic circuit by way of one of said reversers whereby the hydraulic actuating medium is rendered available for actuation of said second support shifting motor, an additional serially arranged reversing mechanism in said circuit for determining the direction of actuation of said second support motor, said mechanism including a primary and a secondary reversing valve, and additional delayed action combined decelerating and reversing valve actuatable by the secondary reverser, delay means for determining the responsiveness of the last-mentioned valve to the reverser in coupling the controlled hydraulic actuating medium to said second support shifting motor.
